WILLIAM I. LUTHER, OF ROCHESTER, NEW YORK,

Letters Patent No. 75,557, dated March 17, 1868.

IMPROVEMENT IN BOTTLE-FAUCETS.

The Schedule referred to in these Letters Patent and making part of the same.

TO ALL WHOM IT MAY CONCERN:

Be it known that I, WILLIAM I. LUTHER, of Rochester, in the county of Monroe, and State of New York, have invented a certain new and useful Improvement in Faucets for Champagne-Bottles, &c.; and I do hereby declare that the following is a full and exact description thereof, reference being had to the accompanying drawings, making part of this specification.

Figure 1 is an elevation of my improved device as applied to a champagne-bottle.

Figure 2, a central vertical section of the same.

Figure 3, a cross-section in plane $z z$, fig. 2.

Like letters of reference indicate corresponding parts in all the figures.

My invention consists in the construction and arrangement of the instrument, whereby it is self-acting, closing, as it enters the cork, to exclude the cuttings, and opening, as it passes through, to allow the flow of the liquid, as hereinafter set forth.

In the drawings, A indicates the outer shell or case, having a longitudinal passage, a , for the flow of the liquid, and provided with a screw, b , at the bottom, for entering the cork. In an enlargement, c , of the upper portion of the shell, is fitted a stop-cock, d , as shown. At the lower end of the screw is also situated an opening-point, f , whose small shank g extends up into the passage a suitable distance, having secured to its top a cross-head, h , resting in slots $i i$ to prevent turning, and pressed down by a coiled spring, k , or in some equivalent manner. Thus it will be seen that the point f is always pressed open, except when it is entering the cork, and when thus pressed open there is an unimpeded passage upward till cut off by the stop-cock.

The instrument constructed in this manner is specially adapted for drawing liquor from champagne-bottles, and similar uses where the liquid is forced out by compressed gas, and when it is desirable to exclude atmospheric air. When the faucet is inserted, as shown in fig. 1, it will be seen that any desired amount of the liquor may be drawn, and the remainder retained by simply closing the cock, thus excluding the air.

Faucets for champagne-bottles have been before known, (as in Patent No. 30,920,) but they are not made self-acting, as I have above described. In such cases, after the screw has been inserted through the cork, the point f , which is in fixed contact with the seat of the screw, must be opened by some positive movement of the shell above, such as screwing down. In my case there is no such movement as this. When the point is pressed into the cork the point is self-closing, and when it has passed through it is self-opening, being thus automatic in its action, and not fixed, as in the cases above stated.

The only object of the closing of the point in my instrument is simply to exclude from the passage a cuttings of the cork made by the screw which might otherwise clog at the point where the spring k is inserted. The instrument works itself through the cork entirely closed at the lower end, but the moment it has passed it is free to allow a flow of the liquid.

The construction of the cross-head h and the spring k is such as to allow an unimpeded passage, for the cross-head is simply a piece of wire, occupying but little space, and the spring is also small. The resting of the cross-head in the slots $i i$ to prevent turning, also insures a better action by keeping all the parts in place. This arrangement, by leaving a maximum passage open, prevents sticking and gumming, which is a source of great difficulty in other devices of the kind where the passage is contracted.

So far as I am aware, the isolated stop-cock d , in combination with the self-acting point, is original with myself. By its employment I avoid the great expense of screws and other attachments, as in the cases before referred to, and also prevent sticking and gumming up. It is in the simplest and most effective form. In addition to its functions as a stop-cock, it also serves as the handle by which the instrument is operated.

It will be seen that the device may be employed as an ordinary corkscrew, independent of its special use as a champagne-faucet.

I do not claim broadly an instrument in which a point is combined with a hollow screw for drawing champagne, &c., as I am aware that the same is not new.

What I claim as my invention, and desire to secure by Letters Patent, is—

1. An automatic faucet for champagne-bottles, &c., in which the passage at the end of the screw self-closes in entering the cork, and self-opens when passed through the cork, substantially as herein set forth.
2. The combination of the independent stop-cock *d* with the automatic point *f* and screw *b*, operating substantially as and for the purpose specified.
3. The special construction and arrangement of the parts, consisting of the case *A*, cock *d*, screw *b*, point *f*, shank *g*, cross-head *h*, and spring *k*, operating as described, and for the purpose set forth.

In witness whereof, I have hereunto signed my name in the presence of two subscribing witnesses.

WM. I. LUTHER.
